Attorney

UNITED STATES PATENT OFFICE.

THOMAS GREGORY, OF CLEVELAND, OHIO.

HAIRPIN.

1,423,606.

Specification of Letters Patent. Patented July 25, 1922.

Application filed August 25, 1921. Serial No. 495,242.

To all whom it may concern:

Be it known that I, THOMAS GREGORY, a citizen of the United States, residing at Cleveland, in the county of Cuyahoga and 5 State of Ohio, have invented certain new and useful Improvements in Hairpins, of which the following is a specification.

This invention relates to hair pins, and it comprises a pin in which one arm is formed 10 of two members pivotally connected to each other and normally spaced at the top beyond the pivot whereby the lower ends of the arms may be opened when the pin is inserted to clamp the hair between them.

15 An object of the invention is the production of a hair pin that will not become displaced when in use.

20 A further object is the provision of a pair of arms that will clamp the hair between them.

A further object is the provision of means for spacing said arms to permit insertion and removal of the pin.

In the accompanying drawings, I have 25 shown one embodiment of the invention. In this showing:

Figure 1 is a front elevation,

Figure 2 is a side elevation,

Figure 3 is a perspective view, and,

30 Figure 4 is a side elevation showing the clamping arms in spaced relation.

Referring to the drawings, the reference numeral 1 designates one arm of the hair pin constructed in the usual manner. Adjacent 35 the upper end, the material forming the arm is split, forming two members 2 and 3. These members are looped in the usual manner, the loops being normally spaced from each other, as shown in Figures 2 and 3 of the drawings. Beyond the loop, the member 40 2 is provided with a curved portion 4 and the member 3 is coiled around the member 2, passing through the curved portion, as at 5. The construction provides a pair of arms 6 and 7, arranged parallel to and in contact 45 with each other (see Figure 3). These arms may be provided with coils 8 and 9 respectively adjacent their lower ends and assist in holding the pin in the hair.

50 In using the pin, the parts are normally in the position shown in Figure 2 of the drawings, with the loops of the members 2 and 3 spaced from each other and the arms

6 and 7 in contact with each other. When the pin is to be inserted in the hair, the 55 loops 2 and 3 are moved toward each other to the position shown in Figure 4 of the drawings, swinging the arm 7 on its pivot and spacing it from the arm 6. The pin is then inserted in the hair and the loops released, the resiliency of the wire or other material returning the arm 7 to its normal position adjacent the arm 6 and clamping the hair between the arms to securely hold the pin in position. 60

65 It is to be understood that the form of the invention herewith shown and described is to be taken as a preferred example of the same, and that various changes in the shape, size, and arrangement of parts may be resorted to without departing from the spirit of the invention or the scope of the subjoined claims. 70

Having thus described my invention, I claim:

75 1. A hair pin formed of a piece of wire substantially U-shaped, said wire being split adjacent the upper end of one arm forming a pair of members, said members being extended to form loops spaced from each other, 80 and being then extended to form an arm substantially parallel to said first mentioned arm, said members being coiled about each other adjacent said spaced loops to pivotally connect them to each other, the portion of 85 said members beyond said pivot being parallel to and normally contacting with each other. 85

90 2. A hair pin formed of a piece of wire substantially U-shaped, said wire being split adjacent the upper end of one arm forming a pair of members, said members being extended to form loops spaced from each other in the plane of said arms, said members being then extended to form an arm substantially 95 parallel to said first portion and being pivotally connected to each other adjacent said spaced loops, the portion of said members beyond said pivot being parallel to and normally contacting with each other. 100

In testimony whereof I affix my signature in presence of two witnesses.

THOMAS GREGORY.

Witnesses:

Ross M. WILSON,
WILLIAM RUEHR.
